INVENTOR.

Edgar S. Doughty
BY *John C. Stryker*

ATTORNEY

UNITED STATES PATENT OFFICE.

EDGAR S. DOUGHTY, OF RED WING, MINNESOTA.

TOY CANNON.

Application filed August 29, 1924. Serial No. 734,964.

To all whom it may concern:

Be it known that I, EDGAR S. DOUGHTY, a citizen of the United States, residing at Red Wing, in the county of Goodhue and 5 State of Minnesota, have invented new and useful Improvements in a Toy Cannon, of which the following is a specification.

The object of this invention is to provide a compact and durable toy cannon adapted to 10 be readily manipulated to impel a projectile with unusual accuracy. This invention also includes certain other novel features of construction, which will be pointed out in the following specification and claims.

15 Referring to the accompanying drawings, which illustrate the best form of my device at present known to me; Figure 1 is a plan view of my improved toy; Fig. 2 is a side elevation of the same; and Fig. 3 is a side 20 view of a projectile for the same.

The cannon is supported upon a broad base 4, carrying a pair of rigid standards 5. Pivotaly supported upon pins 6 in the standards 5 is an arcuate body member 7 25 which carries a cylindrical member 8. A barrel 9 projects from the periphery of the member 8, while a hollow, hemispherical member or bulb 10 of resilient material caps the member 8. Communicating with the 30 interior of the bulb 10 is a passage 11 in the member 8 which also connects with an axial bore 12 in the barrel 9. Projectiles for the cannon are formed, as shown in Fig. 3, with a spindle 13 adapted to be inserted in the muzzle of the barrel 9 and a 35 head 14 which forms an abutment for the muzzle when the spindle 13 is inserted in the bore. A handle 15, rigidly secured to the back of the arcuate member 7, is adapted to be manipulated to aim the cannon.

40 As will be readily understood, the cannon is loaded by inserting the spindle 13 in the muzzle of the barrel 9 as indicated in dotted lines in Figure 2. By manipulating the handle 15 with one hand, the barrel 45 may now be aimed at a suitable target. To discharge the projectile 14, the bulb 10 is depressed by a quick movement of the free hand to thereby expel the air through the 50 passages 11 and 12 against the projectile.

Operation of the device is greatly facilitated by placing the bulb 10 directly above the pivotal support and in alignment with the handle 15 and barrel 9. By the formation of the projectile with the head 14, the 55 possibility of jamming in the bore is precluded and the maximum effect of the air upon the projectile is secured. It will be noted the cannon is very compact and there are no parts which are liable to wear rapidly or get out of order.

Having described my invention what I claim as new and desire to protect by Letters Patent is:

1. A toy cannon comprising a cylindrical 65 body member, a barrel projecting from the periphery of said member, a pivotal support for said member, and a hemispherical bulb of resilient material capping said body member, said body and barrel being 70 formed with passages for air communicating with said bulb, and said bulb being adapted to be compressed to expel air through said passages.

2. A toy cannon comprising a body member, a barrel projecting from one side of said member, a support for said member and a resilient compression member formed to contain air and mounted on said body member, said barrel and body being formed 75 with passages for air communicating with the interior of said compression member, and said compression member being adapted to be depressed to expel air through said passages.

3. A toy cannon comprising a base plate having a pair of standards thereon, a cylindrical body tiltably mounted between said standards, a barrel fixed on the forward periphery of said body, said barrel and 90 body being formed with passages for air, a resilient cap for said body member formed with an air chamber in communication with said passages, and a handle projecting rearwardly from said body.

95 In testimony whereof, I have hereunto signed my name to this specification.

EDGAR S. DOUGHTY.
